[57] **CLAIM**

The ornamental design for a downdraft grill for a cooking appliance, as shown and described.

DESCRIPTION

FIG. 1 is a perspective view of the downdraft grill for a cooking appliance according to the present design;

FIG. 2 is a right side elevational view of the downdraft grill for a cooking appliance of FIG. 1, with the left side elevational view being a mirror image thereof;

FIG. 3 is an elevational view of one end of the downdraft grill for a cooking appliance, with the other end being a mirror image thereof;

FIG. 4 is a top plan view of the downdraft grill for a cooking appliance;

FIG. 5 is a bottom plan view of the downdraft grill for a cooking appliance; and,

FIG. 6 is an upper front view of the downdraft grill for a cooking appliance of the present invention shown embodied in a cooktop of an appliance.

The broken lines in the drawings are for illustrative purposes only and form no part of the claimed design.
